UNITED STATES PATENT OFFICE.

LONIE R. PENNINGER AND DANIEL E. TUCKER, OF CONCORD, NORTH CAROLINA.

JACQUARD MECHANISM FOR LOOMS.

Application filed December 11, 1922. Serial No. 606,303.

To all whom it may concern:

Be it known that we, LONIE R. PENNINGER and DANIEL E. TUCKER, citizens of the United States, residing at Concord, in the county of Cabarrus and State of North Carolina, have invented a new and useful Jacquard Mechanism for Looms, of which the following is a specification.

This invention relates to jacquard mechanism for looms.

Heretofore it has been the practice to use paper cards with jacquard mechanisms but after the cards have been used for some time the same become torn and otherwise mutilated with the result that unless new cards are provided or the old cards properly patched, the fabric produced will contain faults greatly reducing the value thereof or else necessitating the discarding of the fabric. Injury to the cards results not only from the ordinary wear and tear to which they are subjected but also from the failure of the cards to accurately aline with the needles cooperating therewith. It has not been possible to use cards successfully if made of any material other than paper because should the cards be improperly positioned while passing through the machine they would, unless formed of a comparatively soft yielding material, so injure the ends of the needles as to render the cost of upkeep excessively high.

It is an object of the present invention to provide a jacquard mechanism whereby sheet metal cards can be used without danger of injury to any of the parts of the mechanism and without necessitating frequent repairs to the cards or substitution of new cards.

Another object is to provide jacquard mechanism which operates the needles by fluid pressure, the action being quick and accurate whether or not the card perforations accurately match the needles controlled thereby.

Another object is to provide simple and sufficient means for actuating the series of pattern cards in properly timed relation with the fluid controlling means whereby, immediately following the placing of each card in active position, the fluid will be directed through the card under pressure to actuate those needles connected to the lifter hooks to be disengaged from the griff knives.

Heretofore in the operation of jacquard

mechanism the actuation of the needles has brought the lifter hooks into position for engagement by the griff knives. It is an object of the present invention to reverse this action whereby the actuation of the needles will throw the lifter hooks out of operative relation with the griff knives.

A still further object is to provide pattern cards formed of thin sheets of metal so connected as to eliminate the objectionable lacing heretofore required.

Another object is to provide fluid pressure needle operating means which is simple and compact in construction and formed of few parts none of which is likely to get out of order.

With the foregoing and other objects in view which will appear as the description proceeds, the invention consists of certain novel details of construction and combinations of parts which will be hereinafter more fully described and pointed out in the claims, it being understood that various changes may be made in the construction and arrangement of the parts without departing from the spirit of the invention as claimed.

In the accompanying drawings the preferred form of the invention has been shown.

In said drawings—

Figure 1 is a view showing, in diagram, a jacquard mechanism including the present improvements.

Figure 2 is an enlarged view partly in section and partly in elevation of the mechanism constituting the present invention.

Figure 3 is a section on line 3—3 Figure 2, some of the pattern cards being removed but indicated by broken lines.

Figure 4 is a section on line 4—4 Figure 3.

Figure 5 is an elevation of portions of two pattern cards, showing the hinge connection therebetween.

Figure 6 is an enlarged section on line 6—6 Figure 3.

Referring to the figures by characters of reference 1 and 2 designate the upper griff knives arranged in pairs and located beneath the upper hooks 3 and 4 respectively of the lifter wires 5. These wires are provided with lower hooks 6 adapted to rest on and to be supported normally by the lower grate or griff plate 7 as shown particularly in Figure 2.

The wires 5 are crossed by the usual needles 8 which are coupled in the usual manner to the wires, the needles being arranged in groups as shown and the needles 5 of one group being thrust or yieldingly pressed toward the right by springs 9 while the needles of the other group are also provided with springs 9 for thrusting or pressing them toward the left. See Figure 1.

10 It might be stated that in the structure shown the wires carrying the hooks 3 are connected to the needles of one group while the wires carrying the hooks 4 are connected to the needles 8 of the other group.

15 The machine thus far described and which has been illustrated in Figure 1, is a double machine and as the needles of each group are operated in the same manner as the needles of the other group, the description of the mechanism at one end of 20 the machine will apply to the mechanism at both ends.

All the needles 8 of one group are slidably mounted, at one end, in a needle board 10 having a number of openings extending therethrough equal to the number of needles 25 in the group. The needles 8 do not extend entirely through the board 10 but terminate between the faces of the board.

30 Mounted on one face of the needle board is a plunger board 11 having a number of openings 12 extending therethrough and registering with the needle receiving openings in the board 10. A guide block 13 is arranged in contact with the board 11 and has a plurality of counterbored openings 14 extending therethrough, the large ends of the openings being concentric with the respective openings 12. The boards 10 35 and 11 and the block 13 can be clamped together by bolts 15 and, if desired, these same bolts can be used for fastening to the block 13 the flanged open end portion 16 of a pressure chest 17. The open face of 40 the chest 17 is recessed as at 18 thus to receive wings or flanges 19 extending from a follower 20 having flanges 21 adapted to fit snugly within the chest and to slide upon the walls thereof. Springs 22 may be interposed between flanges 19 and block 13 45 so as to hold the follower 20 normally pressed away from block 13 as shown in Figure 4, thus to leave a clearance or passageway between the block 13 and the follower 20 through which the pattern cards 23 can pass. The follower 20 is provided with a group of apertures 24 equal in number to the apertures in the block 13 and, therefore, equal in number to the needles 8 50 in one group. These apertures 24 match the apertures 14 in the block 13.

Mounted to slide within each of the openings 14 is a plunger 25 having a piston or enlargement 26 adapted to slide within the counterbored portion of the opening 14.

Each plunger projects through the plunger board 11 and into one of the openings in the needle board 10 so as to bear against the end of the needle 8 in line therewith. Under normal conditions (when the needles 70 and plungers are at rest) the spring pressed needles 8 hold the plungers 25 with their outer ends flush or substantially flush with that face of block 13 nearest the follower 20.

Located beneath the passage between the 75 pressure chest 17 and the block 13 are take-down rolls 27 journaled in suitable supporting brackets 28 and provided with meshing gears 29. A larger gear 30 meshes with one of the gears 29 and rotates with 80 a ratchet block 31 preferably rectangular as shown and provided near each corner with a notch 32. The rolls 27 are adapted to grip the pattern cards 23 and draw them through the machine as hereinafter explained.

Journalized in brackets 33 above the block 13 is a shaft 34 to which is connected the usual cylinder 35 each face of which is of a width equal to the width of one of the 90 pattern cards 23. Extending from each face of the cylinder are centering studs 36 adapted to project into openings 37 provided therefor in the end portions of the 95 cards 23. The cylinder is so located that when it is at rest one of its faces is in line with the passage between the pressure chest 17 and the block 13, as shown in Figure 2. This cylinder has notches 38 in the corner 100 portions thereof.

A yoke 39 is slidably supported by a bracket 40 and has a slide rod 41 extending therefrom and carrying an arm 42 having a cam slot 43. This arm is movably engaged by a plunger rod 44 and by the up and down movement of this rod 44 the slide rod 41 will be caused to reciprocate horizontally relative to bracket 40. The upper arm of the yoke 39 has a dog 45 pivotally connected thereto and another dog 46 is pivotally connected to the lower arm of the yoke. Thus it will be seen that when rod 41 is reciprocated dog 45 will move over the far corner of cylinder 35 and engage within the adjacent notch 38 while, at the same time, dog 46 will move over the far corner of the block 31 and engage in notch 32. When the yoke moves back to its initial position the cylinder 35 and the block 31 will each be given a one 115 quarter rotation with the result that one 120 card will be moved to position between the follower 20 and the block 13 while another card will be moved out of position between the follower 20 and block 13.

A cam 47 rotates with cylinder 35 and is 125 adapted during the completion of each movement of the cylinder, to come against and actuate the arm 48 of a controlling valve 49. This valve is mounted in a pipe line 50 used for directing air or other fluid under 130

pressure to the pressure chest 17. The valve is normally closed.

Located below the rolls 27 and in the top of the pattern cards suspended from the 5 rolls are angle rails 51 forming a card rack. The pattern cards are formed of thin sheet metal and are connected together by thin metal hinges 52, the alternate pintles 53 being extending laterally from the cards as 10 shown at 53 in Figure 5. Thus it will be seen that as these pintles, which extend only from the hinges at every other joint between the cards, come against the rails 51 of the card rack they will gather up the cards 15 and support them in folds, as shown in Figure 1, preparatory to being drawn upwardly to the cylinder 35. Obviously the cards can thus be arranged in an endless belt so as to pass through the machine inter- 20 mittently.

The pattern cards instead of being provided with openings to allow actuation of the needles 8 in order to bring the hooks 3 or 4 into position over the griff knives, have 25 the openings 23' so located as to aline with those needles to be shifted for the purpose of removing the hooks from the paths of the griff knives. This action is the exact reverse of that which takes place in the 30 jacquard mechanisms now used.

Assuming that the cards have been properly perforated and assembled for the purpose of producing a desired pattern, the mechanism is set in motion. As soon as a 35 pattern card has been brought to position between the follower 20 and the block 13 the valve 49 is momentarily opened thus to admit fluid under pressure to the chest 17. As the result of this action the follower 20 is 40 shifted against the action of its springs 22 and into contact with the card 23 in the path thereof. Thus the card will be clamped against block 13 and pressure can only escape through those openings 24 registering with openings 23' in the card 23. The 45 pressure thus escaping can only enter those openings 14 communicating with the openings 23' in the card. Consequently the plungers 25 located in the pressure receiving openings 14 will be shifted longitudinally by the pressure and will thrust longitudinally those needles 8 contacting with said plungers. Thus the wires connected to the shifted needles will be moved away from 50 their normal positions so that their hooks will not be actuated by the griff knives. As soon as pressure is cut off from the chest 17 and the griff knives have been actuated, the springs 9 return the needles 8 and the 55 plungers 25 to their normal positions, the pressure in the chest escaping along the pattern card and through the passage in which the card is located. Springs 22 will of course move the follower 20 back to its initial position. Following this actuation of the parts 60

the yoke 39 will be shifted to rotate cylinder 35 and block 31 another quarter turn thus to bring another pattern card into controlling position.

It is to be understood that any suitable 70 means, such as a spring 54 can be used for shutting valve 49 as soon as it is released from its actuating cam 47.

Importance is attached to the fact that the jacquard mechanism herein described 75 permits the use of metal pattern cards and as the action of the needles is reversed from that ordinarily followed, there is no danger of the needles becoming bent or otherwise injured if, for any reason, the holes in the 80 pattern cards do not accurately aline with the needles. As before pointed out the use of metal cards is advantageous because such cards cannot be injured in the machine and will last practically indefinitely. 85

What is claimed is:

1. In a jacquard mechanism for looms the combination with needles, and needle actuating plungers separate from and co-operating with the respective needles, of a 90 follower having apertures therein alining with the respective plungers, means for directing a pattern card into position between the follower and the plungers, and means for actuating the follower to grip 95 the card and supply fluid under pressure to the apertures in the card.

2. In a jacquard mechanism for looms the combination with needles, and plungers 100 cooperating with the respective needles, of a follower having apertures therein alining with the respective plungers, a pattern card, means for feeding the same to position between the plungers and the follower, and means for directing fluid under pressure 105 against the follower to grip the card, said card constituting means for releasing fluid under pressure to selected followers.

3. In a jacquard mechanism for looms the combination with needles, and plungers 110 cooperating with the respective needles, of a pressure container, a follower movable relative thereto and having apertures alining with the respective plungers, and means for directing pressure into the container to actuate the follower and grip a pattern card, said follower constituting means for releasing pressure through the gripped card to selected plungers. 115

4. In a jacquard mechanism for looms 120 the combination with needles, of plungers cooperating with the respective needles, a block constituting a guide for the plungers, a follower having apertures alining with the respective plungers, a series of connected pattern cards, means for intermittently actuating the cards to successively position them between the block and follower, and means for directing pressure against the 125 follower to grip a card between the follower 130

and block and release pressure through the pattern card to selected plungers.

5. In a jacquard mechanism for looms the combination with needles, plungers co-operating with the respective needles, and a pressure actuated follower, of a cylinder, take down rolls, said cylinder and rolls constituting means for engaging and supporting a series of pattern cards, means for 10 intermittently actuating the cylinder and rolls to successively position pattern cards between the follower and plungers, and means controlled by the actuation of the cylinder for momentarily directing pressure 15 against the follower to grip a pattern card and to release pressure through the card to selected plungers.

6. In a jacquard mechanism for looms

the combination with a cylinder, take down rolls, and means for simultaneously actuating the cylinder and rolls intermittently, of needles, plungers cooperating with the respective needles, a guide block for the plungers, a follower having apertures and cooperating with but normally spaced from the block, said follower and block being positioned between the cylinder and rolls, and means for intermittently directing pressure against the follower to shift it toward the block.

In testimony that we claim the foregoing as our own, we have hereto affixed our signatures.

LONIE R. PENNINGER.
DANIEL E. TUCKER.
